(57) **CLAIM**

The ornamental design for an instrument panel for automobile as shown and described.

DESCRIPTION

FIG. 1 is a front and left perspective view of an instrument panel for automobile showing my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof; and,

FIG. 7 is a right side elevation view thereof.

The claimed design is indicated by the relatively dark portions in the figures, while the relatively light and de-emphasized portions form no part of the claimed design.

1 Claim, 7 Drawing Sheets
